(57) **CLAIM**

The ornamental design for a window treatment, as shown and described.

DESCRIPTION

FIG. 1 is a perspective view of a window treatment showing our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment thereof;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines illustrate portions of the window treatment which form no part of the claimed design.

The break lines shown in dash-dot broken lines in FIGS. 9-16 symbolize breaks in the length of the article in which the claimed design is embodied. The appearance of any portion of the article between the dash-dot break lines forms no part of the claimed design.
